PUNCH PRESS

Otto E. Seiffert, Union, N. J.

Application November 17, 1936, Serial No. 111,214

16 Claims. (Cl. 29—34)

My invention relates to punch presses and has particular reference to presses adapted to form various articles from sheet metal.

The object of my invention is to provide a punch press which can be used to produce several individual parts and to assemble them into a more or less complete article during one cycle of operations of the press. For this purpose I provide means to support several dies producing a corresponding number of pieces during each stroke of the ram of the press, there being preferably several strokes of the ram during one revolution of the main flywheel of the press. I also provide supplementary reciprocating members, also operated by the main flywheel, like the ram, which can be provided with means to support various tools for performing additional operations on the pieces produced by the dies, also for assembling these pieces together, including certain parts delivered to the press from the outside sources.

Another object of my invention is to provide means for stopping and starting the driving mechanism within several cycles or a fraction of a cycle, the stopping means being manually controlled, including a remote electrical control. For this purpose I provide a clutch, preferably of a jaw type, between the driving flywheel and the driving shaft in the press, and a cam-shaped bushing on the driving shaft, which is under action of springs tending to press it against the clutch thereby engaging the latter. The cam is moved by a pin in the frame, which can be moved in and out of engagement with the cam. By releasing the pin, the driving shaft can be made to stop at a desired point in the operating cycle of the press, for instance, when the ram and the reciprocating members are moved away from the dies.

Another object of my invention is to provide means to individually feed stock to the different dies and tools, also to feed separately prepared parts to be assembled with the articles made in the dies. I also provide means to adjust the rate of feed simultaneously for different dies and separately for each die. For this purpose I provide adjustable operating levers and replaceable or changeable gears for the feed mechanism.

Another object of my invention is to provide a plurality of sliding bars or slides radially extending from the operating zone at the dies to the sides of the press, the slides being operated by rotary cams mounted on exposed ends of shafts operated by the main driving shaft. With this arrangement it is possible to easily and quickly

replace the various cams without disturbing any other parts of the press, having at the same time a number of slides reciprocating in direction of the operating zone, and which can be arranged to perform various additional operations on the articles being produced by means of various tools mounted on the inner portions of these slides.

Another object of my invention is to provide a number of cam members on the end of each shaft, each cam member operating a separate slide, the slides operated by one shaft being arranged in sliding relation to each other. The cams are preferably made of different diameters, the inner cams being smaller, so that the corresponding slides can be placed under the slides from the outer cams.

Still another object of my invention is to provide additional fixtures or tools for the slides in the form of turret heads and ratchet wheels, so that each slide can be made to perform several different successive operations during its several strokes during one cycle.

With my punch press it is possible therefore to perform on a single machine various operations which would otherwise require the use of several separate presses, drop hammers, assembling machines, and additional manual operations. It is also possible to perform these various operations in a single automatic cycle, thereby obtaining a finished and assembled product directly from the machine without any intermediate manual or other operations.

My invention is more fully described in the accompanying specification and drawings, in which—

Fig. 1 is an elevational view of my punch press employing a toggle drive.

Fig. 2 is a similar view of a punch press employing an eccentric drive, showing also a feeding mechanism.

Fig. 3 is a detail view of a slide drive by cams.

Fig. 4 is a top plan view of the press shown in Fig. 2.

Figs. 5 and 6 are views of a belt buckle as made on my press.

Fig. 7 is a sectional view of a caster head as made on my press.

Fig. 8 is a detail view of a slide with a dial mechanism for assembling certain parts of an article.

Fig. 9 is a detail view of a device for assembling parts of the caster head shown in Fig. 7.

Fig. 10 is a detail view of a turret mechanism for making the shell of the caster head.

Fig. 11 is a detail view showing the caster shell in the process of being assembled by the turret mechanism shown in Fig. 10.

Fig. 12 is a detail view showing a preliminary stage in the assembling of the caster head.

Fig. 13 is a detail view showing another preliminary stage in the assembling of the caster head.

Fig. 14 is a top plan view of the machine fully assembled.

My punch press consists of a frame 1 with a bolster 2 which may be formed integrally with the frame as shown. A ram 3 is slidably supported on gibs 4 and has a face plate 5 operating dies 6, 7 supported on the face of the bolster 2 in a usual manner. The gibs and the sides of the ram are made with a slight taper so as to provide a closer fit when the ram is operating the dies than when it is moved away from them. This insures more accurate fit of the dies and conserves the cutting edges. The gibs are shown located horizontally, although, of course, they can be made inclined with a correspondingly inclined bolster. In a particular embodiment shown in Fig. 1, the ram is reciprocated against the bolster by a toggle mechanism consisting of levers 8 and 9 pivotally connected at 10 and 11 with the ram and a toggle block 12. The latter is held by tie rods 13 and 14, the latter being cast in the frame 1. The lever 9 is pivoted at 15 to one end of a toggle rod 16, the other end of which is journaled on an eccentric portion 17 of a shaft 18. The latter has a gear 19 in mesh with a gear 20 on a main driving shaft 21. The gear 20 is shown of a larger diameter than the gear 19 so that the ram makes more than one stroke for each revolution of the main shaft. A gear 22 on a shaft 23 is connected by a belt or chain 24 with a hopper or feeder 25 for small parts which are delivered through a chute 26 to dies for assembling with the stampings. These parts are also shown in Fig. 4, the gear 22 being shown in dotted lines and provided with a pulley 27 for the belt. A flywheel 28 freely rotates on the outer extension of the driving shaft 21 and can be connected by a belt with a suitable source of power (not shown) for its operation. The flywheel has one or more teeth 29 which can engage corresponding slots 30 in a sliding jaw clutch 31. The clutch 31 is keyed to the shaft 21 so that it connects the flywheel with the shaft when the tooth 29 engages one of the slots 30. The clutch is pressed against the flywheel by springs 32. It has an enlarged cylindrical portion 33 with a cam-shaped edge 34 engaged by a pin 35 slidably supported in a bearing 36 in the frame. The pin is pressed by a spring 37 against the clutch 31. When the clutch is engaged, it rotates with the shaft 21, and the pin 35 follows the curvature of the cam-edge 34 until a projecting portion of the cam engages the pin thereby forcing the clutch back and releasing the tooth 29. The position of the hump on the cam is arranged so that the press stops when the ram is moved away from the bolster to facilitate work with the dies. The pin 35 has an extension 38 pivoted at 39 to a bar 40 having a pedal 41 at one end and being pivoted at the other end on a pivot 42. By stepping on the bar, the pin 35 is withdrawn and cannot then stop the machine. The pin has also collars 43 which can be engaged by a slot 44 in a hand lever 45 pivotally supported at 46 on the frame. In order to release the clutch for continuous operation of the press, the pedal 41 is depressed and the lever 45 turned by hand until its slot engages

the pin between its collars 43 thereby retaining the pin in an inoperative position. To stop the press, the lever 45 is turned back thereby releasing the pin, which snaps in its position at the cam and stops the press as soon as the hump of the cam engages the pin. The lever 45 has an extension 47 connected with a plunger 48 of a magnet 49. This magnet is controlled by push buttons at convenient places and can be used for stopping the press from various remote points. It cannot be used to start the press, however, and serves principally as a safety device and to insure quick stopping if there is any fault in the press operations.

A modified form of drive for the ram is shown in Figs. 2 and 4. The frame 50 has gibs 51 for a ram 52. A stub shaft 53 is journaled in a clevis 54 at the end of the ram, the shaft having a hole for the threaded end of a driving rod 55 held by nuts 56. The other end of the rod 55 has a bearing for an eccentric portion of a shaft 57 connected by a gear 58 with the driving gear 20.

The bolster 2 which supports dies 6 and 7 shown in Fig. 1, also supports feed slides 59 on rails 60, there being individual slides for each die. Two slides are shown but there may be a larger number of them arranged side by side, all operated by individual levers 61, 62, connected with the slides by links 63. The levers 61 and 62 are connected with gears 64, 65 rotatively mounted between collars 66 on a shaft 66 fitted by its ends in the sides of a frame extension 67. The gears 64 and 65 are in mesh with gears 68 and 69 keyed on a shaft 70 journaled in the sides of the extension 67 and having a lever 71 on one end. The lever 71 has a slot 72 for a bolt 73 connecting it to one end of a link 74 the other end of which is connected by a bolt 75 passing through a slot 76 with a lever 77. This lever is pivoted at 78 in a bracket 85 and has a sliding block 79 with a pin 80 engaging a cam slot 81 in a cam cylinder 82 mounted on the end of a shaft 57. By changing the position of the bolts 73 and 75 in the levers 71 and 77 it is possible to change the rate of feed for stock 84, usually in the form of strips of metal. The feed can be also changed individually for each slide 69 by changing the respective gears 64 and 68 or 65 and 69. The cam slot 81 may be made for different length of feed stroke, and it can be made to produce one or more feed strokes during one revolution of the shaft 83.

The shaft 57 has a second cam cylinder 86 with a cam slot 87 engaging a pin 88 on the end of a slide 89. The other end of the slide has a notch 90 or similar arrangement for holding different tools used for supplementary operations on parts stamped out by the dies from the stock 84. The end of the shaft 57 has a bevel gear 91 in mesh with gears 92 and 93 preferably at right angles to the gear 91. The gears 91, 92, and 93 are located in the middle portion of the press near the dies and substantially at the sides of an opening 94 for scrap falling from the dies. The gears 92 and 93 are mounted on the ends of shafts 95, 95 extending outside of the frame and having on their outer exposed ends cam cylinders 96 and 97. The cylinders have cam grooves 98 and 99 for rollers 100 and 101 on the ends of slides 102 and 103. The slides 102 are placed under the slides 103, which is made possible by having the cam grooves 98 of a smaller diameter than the grooves 99, as may be seen more clearly in Fig. 3. The outer end of the inner slide 102 has an additional roller 104 resting against the inner

flange of the outer cam cylinder 97, thereby providing a better bearing surface for exerting a pressure on the work by tools on the inner ends of the slides. The rollers 100 are smaller and lighter and are used only or mostly for retrieving the slide, when it does not perform any heavy duty. Similar cam cylinders 105 and 106 are mounted on the end of a short shaft 107 connected with the driving shaft 21 by spur gears 108 and 109. With this arrangement there are four sets of slides converging by their inner ends to a zone of operations near the main dies 6 and 7 where they can be used to perform various supplementary operations on stampings or similar parts produced by the dies.

The four sets of slides, converging from four different directions to the zone of operations, are driven by three central bevel gears and two outer spur gears. This arrangement permits to have 20 a free space for the scrap hole 94 where otherwise may have been the fourth bevel gear for the slides.

By combining operations by the tools on the slides with the operations performed by the main dies, it is possible to produce more or less complicated articles entirely automatically. One example of such articles is shown in Figs. 5 and 6 representing a belt buckle 110 with a clasp 111. Another example is shown in Fig. 7 representing a stamped head of a caster with a disc 112 wedged between the ends of the head 113 and provided with a central bearing 114. The method of making this article is shown in Figs. 8 to 13 incl. For this work a turret head 114' is employed rotatively mounted on a pin 115 fitted in the end portion of the slide 102. The head 114 works against a die 116 by its tools 117, 118, and 119. A ratchet wheel 120 is mounted on the head 114 and is turned by a pawl 121 pivoted at 122 on a stationary portion of the frame of the press. A punch 123 is also mounted on the slide 102 and works in cooperation with a die block 124. A suitable punch (not shown) pierces holes in the strip 84' into which bearing bushings 114 are fed by a chute 26 from the hopper 25. Discs 112 are then punched out of the strip 84' and left in a circular die 125 in a hole 126. The punch 123 separates a blank 127 from the strip 84. The blank is then formed into the head 113 in the die 116 by the tool 117 as shown in Fig. 10. The slide 89 turns the die 25 by a pawl 128, bringing the assembled disc 112 with the bushing 114, which has been riveted in its place by a suitable tool (not shown), under a guiding block 129. A plunger 130, operated by a slide 103, brings the disc 112 in alignment with a slide 131 moving in a slot in the head 129 by the end of a lever 132. The lever 132 is mounted on a pin 133 supported on the frame of the press. The other end of the lever has a pawl 134 operated by the slide 89 having a shoulder 135. The slide 131 moves the disc 112 into the open end of the head 113 whose flanged upper portion remains sufficiently open on top at the side to admit the disc. A movable guide 136 temporarily retains the disc until it is wedged in its place by the tool 118 as shown in Fig. 13. The tool 119 finally closes the edges of the head 113 over the disc, and the assembled part is ejected by an arm 137 fitted on the frame of the press. A pin 138 guides the disc 112 when it enters the bushing 114.

One of the important advantages of my press is that it can automatically perform a variety of operations usually requiring several separate machines plus some hand labor. By combining sev-

eral independent feeds for separate dies, it is possible to make several separate stampings by a single stroke of the ram; the working stroke of the ram occupying a fraction of one revolution of the driving shaft, the remaining portion of the revolution can be used for performing additional operations on the stampings delivered from the main die, using for these additional operations multiple slides working from four different directions, there being more than one slide in each direction; these additional operations can be further expanded or elaborated by using ratchet operated dials and turret heads on the slides; using these various devices to assemble together parts made on the different dies of this press, including also parts made on other machines and delivered by separate feeding devices.

Another important advantage of my press is that it can be easily changed from a toggle ram to an eccentric ram, the rest of the machine including its drive remaining unchanged. This is important when it is desired occasionally to change the type of work on the press: for light work, where a low power expenditure is preferred, the eccentric drive will be used; and for a heavy work it may be changed over to the toggle drive.

Another important advantage resides in the construction of my clutch. The cam 34 can be provided with as many projections to be operated by the pin 35, as there are strokes of the ram in one revolution of the driving shaft, and the projections can be located so that the clutch becomes disengaged before the stroke of the ram, thereby stopping the machine in time to prevent the operation of the ram when the operation is no longer wanted or is dangerous to the work. This feature of the clutch is especially useful in connection with the electromagnetic control of the pin 35. The magnet can be controlled by push buttons placed conveniently in various places around the machine where the operator may need them for stopping the ram in time to prevent its operation, or where some adjustments may be needed. The magnet can be also controlled automatically, and some of the applications of the automatic control are shown in Figs. 8 and 10. Here an automatic switch is shown, consisting of a stationary contact plate 138 mounted on an insulation post 139 on the bolster or on the die between the two strips of sheet metal 84 and 84' being fed into the dies. The plate 138 has two legs extending over the two strips. Additional contact plates must be provided in case there are more than two strips being fed into the dies. A resilient strip or plate 140 is mounted on an insulation post 141, the plate 140 being also provided with two legs in case of two strips of stock being fed into the dies.

A lug or button 142, made of an insulating material, extends from the plate 140 down and rests against the strip 84 or 84', thereby keeping the end of the plate 140 away from the plate 138. The plates 138 and 140 are included in the circuit of the magnet 49, so that this circuit remains open as long as there is a strip of stock being fed into one of the dies. As soon as one of the stock strips is all used up, the button 142 drops down and the end of the resilient contact plate 140 comes to rest against the end of the plate 138, thereby closing the circuit for the magnet 49 and stopping the machine. One of the electromagnetic indicators 143 of an ordinary construction, preferably mounted in an indicator board 144 on the side of the press, is also included in the circuit of the contact plates 138 and 140, so that

the operator will instantly know the reason why the press stopped, by glancing at the indicator board. Other indicators, suitably numbered or provided with symbols or words, are connected to various other automatic switches on the press. 5 Another automatic switch, shown in conjunction with the plate 140 in Figs. 8 and 10, although it can be used independently, is used to stop the press in case the dies and other devices become defective and will not let the strips, moved by the feeding devices, to pass through, so that the strips will begin to buckle. This switch consists of a stationary contact plate 145, shown as an extension of the plate 140, and a movable resilient plate 146 located under the stationary plate and supported on an insulation post 147. The plates 145 and 146 are included in the circuit of the magnet 49 and close this circuit when the strip 84 becomes buckled, rising from the surface of 10 the bolster or die, and pressing the plate 146 against the plate 145. A separate indicator is included in this circuit.

Another automatic switch is formed with a photoelectric tube 148 placed under a hole 149 in the die or in the press, over which is moved the strip 84 or 84' after a punching operation. An ordinary electric lamp 150 is placed opposite the photocell 148 and energizes the latter when the light passes through a hole 151 punched in the stock by the die. The current in this case is used to render inoperative the magnet circuit which otherwise would be closed by the movement of the strip 84 from the die.

Automatic switches are also used in my press to indicate any defects in forming operations as shown in Fig. 10. Here a resilient contact member 152 is supported on an insulation post 153 and presses by its point on a flange 154 of an article 113 being formed in a bending die. The point is insulated from the rest of the plate. Another contact plate 155, which can be mounted on the same insulation post 153, is adapted to be depressed by the descending arm of the punch 123, thereby bringing the hooked end of the plate 152 in opposition to a hooked end of the plate 155 as shown in Fig. 10. The plates become separated by the flange 154, keeping the magnet circuit disconnected. The circuit becomes closed, however, if the flange is not formed in its proper place, indicating defect in the stock or in the dies.

It is understood that my punch press can be modified without departing from the spirit of my invention as set forth in the appended claims.

55 I claim as my invention:

1. A punch press comprising a bolster and a ram, means to reciprocate the ram against the bolster, a driving member adapted to operate the reciprocating means, an electromagnetic means to render the reciprocating means inoperative, dies on the bolster, means to feed stock into the dies, and a plurality of contact members adapted to be operated by the stock and adapted to render the electromagnetic means operative when the progress of the stock deviates from normal.

2. A punch press comprising a plurality of reciprocating members adapted to support tools, a driving member adapted to successively operate the reciprocating members during its one revolution, an electromagnetic means to render the driving member inoperative before the next operative movement of the next reciprocating member, means to feed stock for the tools, and a plurality of switches adapted to be operated by the stock under action of the tools and adapted to

render the electromagnetic means operative when the results of operations of the feeding means and tools deviate from normal.

3. A punch press comprising a bolster and a ram, a driving member, means to reciprocate the ram by the driving member, a central gear mechanism operatively connected with the driving member, shafts radially extending from the gear mechanism, cam members on the outer exposed ends of the shafts, tool slides adapted to be reciprocated by the cam members, dies adapted to be supported between the bolster and the ram, means to feed stock into the dies by one of the cam members, tools on the slides adapted to operate on the stock in cooperation with the dies, said tools and said dies being adapted to complete their operations during one revolution of the driving member, and means to automatically control said operations and their order of succession.

4. A punch press comprising a bolster and a ram, a plurality of dies adapted to be supported on the bolster and adapted to be operated by the ram, means to reciprocate the ram, a shaft, operative connections between the shaft and the reciprocating means, a driving member, a clutch connecting the driving member and the shaft, means to feed stock individually to the dies, means to adjust the length of feed, a plurality of tool supporting slides in cooperative relation to the dies, and means to individually operate the slides by the driving member.

5. A punch press comprising a frame, a bolster on the frame, a ram movably supported on the frame, means to reciprocate the ram against the bolster, the bolster being adapted to support a plurality of dies, a shaft, means to operate the ram by the shaft, a driving member for the shaft, means to feed stock to the dies, a plurality of cams rotatively and replaceably supported at the exposed portions of the frame, means to rotate the cams by the shaft, slides operatively connected with the cams, and means to support tools on the slides in cooperative relation to the dies.

6. A punch press comprising a frame, a bolster on the frame, a ram movably supported on the frame, means to reciprocate the ram against the bolster, the bolster and the ram being adapted to support respective positions of dies, a driving member, a plurality of shafts extending in different directions outside of the frame, operative connections between the driving member, the reciprocating means and the shafts, cams replaceably supported on the exposed portions of the shafts, means to feed stock to the dies, slides operatively connected with the cams and converging to a point at the side of the dies, and means on the slides to support tools for additional operations on the stock in the dies.

7. A punch press comprising a frame, a bolster formed on the frame, a ram movably supported on the frame, means to reciprocate the ram against the bolster, a driving member, operative connections between the driving member and the reciprocating means, the bolster being adapted to support a plurality of dies, means to feed stock individually to the dies, a common drive for the individual feeding means, a cam member adapted to operate the common drive and operatively connected with the driving member, and means to adjust the common drive for different rates of feed.

8. A punch press comprising a frame, a bolster on the frame, a ram movably supported on the

frame, a driving member, means to reciprocate the ram by the driving member, the bolster being adapted to support a plurality of dies, means to feed stock individually to the dies, a common drive for the feeding means, a shaft operatively connected with the driving member, a cam member mounted on the shaft and operatively connected with the common drive, and means to adjust the rate of feed individually for the separate feeding means.

9. A punch press comprising a frame, a bolster on the frame, a ram movably supported on the frame, a driving member, means to reciprocate the ram by the driving member, the bolster being adapted to support a plurality of dies, a plurality of shafts operatively connected with the driving member, a plurality of cam members on each shaft, slides adapted to be reciprocated by the cam members, and means to support tools on the slides supplementing the dies.

10. A punch press comprising a frame, a bolster on the frame, a ram movably supported on the frame, the bolster being adapted to support a plurality of dies, means to reciprocate the ram against the dies, a driving member operatively connected with the reciprocating means, means to feed stock to the dies into an operating zone, a plurality of shafts radially extending in the frame from the operating zone, a plurality of cylindrical cam members on each shaft, slides extending from the cam members to the operating zone, the slides from the cam members on one shaft being supported in slidable relation to each other, and means to support tools on the inner ends of the slides.

11. A punch press comprising a frame, a bolster on the frame, a driving member, a ram movably supported on the frame and adapted to be reciprocated by the driving member, the bolster being adapted to support dies in an operating zone, a plurality of shafts radially extending from the operating zone, means to rotate the shafts by the driving member, a plurality of cylindrical cam members of different diameters on each shaft, the inner cams being of a smaller diameter, slides extending from the cam members and operatively connected therewith, the inner slides from the smaller cam members being adapted to slide under the outer slides, the inner ends of the slides being adapted to support tools in the operating zone, and means to feed stock to the dies in the operating zone.

12. A punch press comprising a frame, a bolster on the frame, a driving member, a ram movably supported on the frame and adapted to be reciprocated by the driving member, the bolster being adapted to support dies in the operating zone, four shafts extending radially from the operating zone, three outer shafts being connected by bevel gears at their inner ends, a drive shaft operatively connected with the driving member, and spur gears connecting the drive shaft with the fourth shaft and with the oppositely located one of the three shafts, the por-

tion of the frame at the inner end of the fourth shaft being provided with an opening for the removal of scrap.

13. A punch press comprising a frame, a bolster on the frame, a ram movably supported on the frame, the bolster being adapted to support a plurality of dies, slides movably supported on the frame, a driving member, means to independently reciprocate the ram and the slides by the driving member, the slides converging by their inner ends to the zone of operations at the dies, one slide being adapted to support a die on its inner portion, the other slide having a turret head adapted to support a plurality of tools for cooperation with the die, and means to rotate the turret head by the reciprocating movement of the slide supporting the same.

14. A punch press comprising a frame, a bolster on the frame, a ram movably supported on the frame, the bolster being adapted to support a plurality of dies, slides movably supported on the frame, a driving member, means to independently reciprocate the ram and the slides by the driving member, the slides converging by their inner ends to the zone of operations at the dies, the slides being adapted to support tools cooperating with the dies, and a dial rotatively supported on a die and adapted to be rotated by the reciprocating movement of a slide, the dial being adapted to support a die and to transport a portion of work from one set of tools to another.

15. A punch press comprising a frame, a bolster on the frame, a ram movably supported on the frame, a driving member, means to reciprocate the ram by the driving member, the bolster being adapted to support a plurality of dies, a plurality of shafts rotatively supported in the frame, means to rotate the shafts by the driving member, cylindrical cam members on the shafts, slides movably supported on the frame, rollers on the ends of the slides engaging the cam members, the slides being adapted to support tools cooperating with the dies, thrust rollers on the ends of the slides, and flanges on the cam members abutting the thrust rollers, the thrust rollers being adapted to relieve the strain from the guiding rollers during the operating strokes of the slides.

16. A punch press comprising a frame, a bolster and a ram on the frame, means to reciprocate the ram, the bolster being adapted to support dies, slides movably supported in the frame, means to independently reciprocate the slides, the slides being adapted to support tools cooperating with the dies, a dial on a slide adapted to be intermittently rotated by the movement of the slide and adapted to support tools, means to feed stock to the dies and tools in the press, and a hopper adapted to feed semi-finished parts for assembling with the product from the dies and tools.

OTTO E. SEIFFERT.
